DESIGN FOR A CLOTHESLINE REEL

Max A. Le Veck, Dayton, Ohio

Application November 30, 1942, Serial No. 108,909

Term of patent 14 years

To all whom it may concern:

Be it known, that I, Max A. Le Veck, a citizen of the United States, residing at Dayton, in the county of Montgomery and State of Ohio, have invented a new, original, and ornamental Design for a Clothesline Reel, of which the following is a specification, reference being had to the accompanying drawing, forming a part thereof.

Figure 1 is a perspective view of a clothesline reel, showing my new design.

Figure 2 is a top plan view thereof.

Figure 3 is a side elevational view thereof looking in the direction of the arrow 3 shown in Figure 1.

Figure 4 is an end elevational view thereof.

I claim:

The ornamental design for a clothesline reel, as shown.

MAX A. LE VECK.
